UNITED STATES PATENT OFFICE

JOHN CURRIE PATERSON, OF WILLESDEN, LONDON, ENGLAND, ASSIGNOR TO BAKER PERKINS COMPANY, INC., OF SAGINAW, MICHIGAN, A CORPORATION OF NEW YORK

DOUGH-CUTTING MACHINE AND THE LIKE

Application filed July 1, 1929, Serial No. 375,192, and in Great Britain July 26, 1928.

This invention relates to conveying and other means associated with gauge rolls for use in conjunction with dough-cutting or like machines. Considerable difficulties and convenience are experienced in connection with dough-cutting and like machines, particularly those parts which are associated with the gauge rollers, namely, the stripping knife or scraper and the apron or band adapted to receive the dough sheet from the gauge rolls and convey it away for subsequent operations in the machine, as the usual means do not provide facilities for dealing with doughs of different consistencies, variations in the thickness of the sheet and temperature variations, and fail, due to lack in accommodation of these variations and conditions, to convey the dough continuously and smoothly from one point to another without troublesome hitches and stoppages.

The object of the present invention is to overcome the above difficulties by providing improvements which can be readily adapted to the varying conditions and afford means for universal treatment irrespective of such varying conditions and so that the manufacturer may arrange his machine to suit the treatment he individually favors.

With these ends in view the invention comprises the provision of a stripping or scraper element for the gauge rolls adapted readily to be adjusted circumferentially of the lower roll between wide limits so that it may be positioned, while the rolls are running, in the one extreme to a line whereat it is adapted to lead the dough in a more or less horizontal path as it leaves the gauge rolls towards the receiving apron or band and be again adjusted towards the lower end of the vertical diametric plane of the rolls so that the sheet leaves the lower gauge roll in looplike form.

It is preferred that the scraper should be afforded a circumferential adjustment by being carried by a pair of levers pivoted coaxially with the lower gauge roll and having means, such as for example a rack and pinion or segment, adapted to swing these levers from one position to another about said axis.

The invention further consists in supporting a receiving apron, band or web by means

capable of effecting its adjustment horizontally and vertically with a view to affording variations both of the distance of the receiving end of the band from the gauge rolls and also the level or vertical height thereof with respect thereto.

The arrangement for the receiving apron or web may comprise disposing the apron or web drum remote from the gauge rolls instead of having it located adjacent thereto as is customary, and supporting the end of the apron or web which lies towards the gauge rolls upon a comparatively narrow roller or turning support.

The web or apron as a whole or a part thereof may be pivoted or hinged so that the end towards the gauge rolls may be raised or lowered and secured in any adjusted position as desired.

The support for the web or band may be mounted upon a slide or guideway enabling the band as a whole, or part thereof, to be displaced horizontally of the machine.

In the accompanying drawings Figs. 1 and 2 are end and side elevations of a pair of gauge rolls having a scraper element according to the invention.

Fig. 3 is a part diagrammatic side view of a machine comprising the gauge rolls and receiving apron.

Figs. 4 and 5 are detailed views showing adjusting means for the receiving apron.

In carrying the invention into effect according to one convenient mode, the shaft 10 of the lower gauge roll 11 has mounted upon its ends a pair of levers 12 adapted to pivot about the shaft. The outer end of these levers is provided with a support or bearing for a scraper blade. For example, a scraper blade 13 may be mounted upon a shaft 14 the ends of which are supported by the outer hook ends 15 of the lever arms 12. For adjusting the tangential position of the scraper blade adjusting screws 16 are provided which pass through apertures in the ends of the blade and screw into the lever arms. Alternatively, the shaft 14 may have at each end a lever secured thereto and through which a set screw passes and is engaged in an extension or part of the corresponding lever arm.

In order conveniently to displace the scraper circumferentially of the gauge roll, the rear portion of the lever arm is provided on each side of the machine with a rack 17 adapted to engage with a segmental rack 18 or with a worm. The segmental racks or worms are mounted upon a suitable shaft 19 which may terminate in a handle or lever 20 having at its outer end an adjustable pin 21 adapted to enter one or other of a series of pin holes arranged in an appropriate arc, the arrangement being such that the levers 12 may be adjusted in unison. The scraper may be readily swung from one position of adjustment to another while the machine is running and rigidly secured or locked in any adjusted position. It will be appreciated that such range of adjustment enables the scraper, when the machine is started up, to be swung around into a position in which the leading edge of the dough adhering to the lower gauge roll is peeled off and may be directed horizontally towards the receiving band or web.

25 The band or web 22 for receiving the dough from the gauge rolls is conveniently supported, as to its upper lap, upon a table portion 23 the ends of which may be curved or rounded or provided with rollers 24, 26 to serve as turning points for the lower lap. The apron 22 passes around a web drum or driving roll 25 which is located away from the gauge rolls and preferably towards the forward end of the receiving table.

30 The web table 23, web drum 25 and roller 26 may be conveniently supported in side plates or frames 29 which may be mounted upon a slide or on rails carried by a cover plate or upon the side frames of the machine proper so that these web or apron frames may be slid towards or away from the gauge rolls.

35 The web table 23 is mounted in a pivotal manner in slide blocks 27, shown in Fig. 5, thus enabling the end of the table towards the gauge rolls to be raised or lowered about the hinging axis. The slide blocks 27 are adapted to slide in guideways or recesses 28 in the side plates 29 whereby small adjustments of the table toward and away from the gauge rolls may be effected. The slide blocks are locked in their adjusted position by thumb screws 35 carried by the slide blocks and bearing upon plates 42 fixed to the side plates 29. The plates 42 are provided with slots 36 accommodating the shanks of the thumb screws.

40 In order to tension the band 22 when adjustments of the table have been made, the roller 26 is mounted in guide blocks 30 located in the guideways 28, each guide block carrying an internally threaded nut 31 provided with an adjusting screw 32 having a head 33 for convenient manual operation. The screws 32 are adapted to abut against the slide blocks 27 on which the table 23 is

pivoted. It will be appreciated that when the slide blocks have been adjusted and locked to the plate 42, the roller 26 may then be adjusted to the desired position by operating the screws 32.

45 For adjusting the table about its pivotal axis a screwjack supporting device 37 is provided having a roller 38 engaging a suitable bar 23^a on the table.

50 The gauge rolls and apron may be driven in any convenient manner, whereby the relative speeds may be varied as desired. Thus, the gauge rolls may be driven by the gearing 40, 41 from one spindle of a cone speed varying gear 39 while the apron may be driven by a sprocket chain 138 and gears 136, 137 from the other spindle of the gear.

55 The side frames of the machine proper may support a flat cover plate 43 extending beneath the receiving band 22 and in the region of the gauge roller 11 for providing protection for the machine parts within or below the side frames. This cover plate 43, by reason of the nature of the support for the receiving band or apron, is accessible laterally and, consequently, facilitates the removal of any broken pieces of dough which may become collected upon the cover plate during the running of the machine.

60 It will be appreciated that the adjustments above described enable the manufacturer to adjust his receiving band to meet the conditions of the dough sheet or as he may individually choose so that the dough may be led more or less horizontally from the gauge rolls to the receiving band or may proceed in a longer or shorter loop with a large or small gap separating the two runs of the loop. Further, as previously stated, the dough may be delivered on to the receiving band 22 at 65 the same height as it passes between the gauge rolls or it may be delivered in elevated or depressed relationship thereto.

65 According to an alternative arrangement of the band table 23, its right-hand end portion, Fig. 3, may be rigidly mounted on the side frames 29 while the remaining portion of the table, towards the gauge rolls, is hingedly connected to the said fixed part as a flap, enabling the end of the table towards the gauge rolls to be raised or lowered about the hinging axis. Such flap of the table 23 may be adjustably supported by any suitable known means for example, strut members may be provided to which the flap is secured by means of a pin engaging one of a series of holes chosen to afford the appropriate height of the free end of the flap. Alternatively, again, the flap may be mounted upon a strut adapted to afford screw threaded adjustment for raising and lowering its free end.

70 As a further alternative for providing vertical adjustment for the band 22 the whole 75

of the table 23 and its band may be pivoted about the axis of the drum 25.

The fore-and-aft adjustment of the band may be effected by pushing the frame 29 of the table 23 along the slideway and securing it in the desired location or, if desired, such adjustment may be effected by the aid of a rack, or equivalent means, not shown.

10 The invention has been described with reference to a dough cutting machine but it is to be understood that it may be applied to like machines where other kinds of plastic or like material is to be operated upon by power driven rollers.

15 Having thus described my invention, what I claim and desire to secure by Letters Patent is:

1. A dough working machine having a pair of gauge rolls, a circumferentially adjustable scraper blade operatively associated with the lower roll, and blade-positioning devices for effecting such adjustment.

20 2. A dough-cutting or like machine as claimed in claim 1, wherein the scraper blade is carried by a pair of levers pivoted coaxially with the lower gauge roll and gearing adapted to swing said levers about the axis of the roll.

25 3. In combination, an upper and a lower gauge roll, a pair of levers pivoted co-axially with the lower roll, gearing adapted to swing said levers about the axis of said lower roll, a scraper blade pivotally mounted in the levers, and a blade-adjusting device for 35 changing the position of the blade relatively to the levers and the lower roll.

30 4. In combination, an upper and a lower gauge roll, a circumferentially adjustable scraper blade operatively associated with the lower roll, a traveling band adapted to receive material deflected by said blade from said rolls, said band mounted for selective positioning whereby its end which is adjacent the rolls may be adjusted vertically thereto.

40 45 5. A dough-cutting or like machine having rolls and a peripherally adjustable scraping blade therefor, a receiving band mounted for adjustments in elevation of an end thereof and for effecting displacements thereof longitudinally with respect to said rolls, and said scraping means, and a common driving means for said rolls and band.

50 55 60 6. In combination, an upper and a lower gauge roll, a pair of levers pivoted co-axially with the lower roll, gearing engaging said levers to move them in angular adjustment about the axis of said lower roll, a handle for adjustably positioning said gearing, a scraper blade pivotally mounted in the free ends of the levers, and a blade-adjusting device for changing the position of the blade relatively to the levers for spacing variation from the lower roll.

65 In testimony whereof, I affix my signature.
JOHN CURRIE PATERSON.
